COIN CONTROLLED APPARATUS

Elmer L. Lipp, Los Angeles, Calif., assignor, by
mesne assignments, to Refining, Inc., Reno,
Nev., a corporation of Nevada

Application December 15, 1931, Serial No. 581,086

16 Claims. (Cl. 194—9)

This invention relates to improvements in coin controlled apparatus, and more particularly to electric time switches.

The principal object of the invention is to control electric time switches by a plurality of coins, of fixed denomination, to the predetermined cumulative value.

Another object is to delay the operation of the switch until the total coin value has been deposited.

Another object is to cause the preceding coins to divert the final coin in the series to the actuating mechanism.

Another object is to switch on a "consuming power circuit" for a predetermined period of time.

A further object is to dump the actuating coins if the consuming power circuit is opened.

Other objects and advantages will appear as the description proceeds.

Among the advantages of the invention is the accumulation of a sum of coins in the smaller denominations, equal to or greater than a single coin of larger denomination. For instance, coins of greater denomination than half dollars are not in general circulation. In the present instance the invention is adapted to the accumulation of four quarter dollars, before the power switch is operated, in contradistinction to switches controlled by a single coin such as one dollar.

In this manner daily sums of money equal to an installment payment upon the purchase price of a machine may be mechanically collected at a greatly reduced collection overhead. Power consumption may be likewise paid for in advance. In this manner improvident persons are compelled to meet their obligations to the vendor or forego the use of the machine.

It is proposed to add "coin detectors" and other precautionary mechanisms to the coin chute to prevent the effectiveness of spurious coins or other fraudulent operations wherever occasion requires. In the interest of simplicity the present disclosure is confined to the major essentials of the invention.

In this specification and the accompanying drawings the invention is disclosed in its preferred form. It is to be understood, however, that it may be embodied in other forms without departing from the spirit of the invention as defined in the claims following the description.

In the three sheets of drawings:

Fig. 1 is a front elevation of an apparatus constructed in accordance with this invention.

Fig. 2 is a partial vertical section of the same after the required coins have been deposited to initiate its operation.

Fig. 3 is a vertical cross section showing the details of the timing mechanism.

Fig. 4 is a schematic diagram showing the wiring circuits of the apparatus.

In detail, the construction illustrated in the drawings, referring more particularly to Fig. 1, comprises the casing 1, having the lid 2 hinged to the casing at 3—3 and adapted to close the open front of the casing. The latch 4 is mounted at the side of the casing to engage the lid and may be suitably padlocked to prevent access to the contents of the casing by unauthorized persons.

The plate 5 is mounted on the brackets 6—6 within the casing (see also Fig. 3). The base 7 is spaced from the plate 5 by the brackets 8—8 upon which it is mounted. The base 7 has the extension 9 projecting upward through the top of the casing 1. The bifurcated spacing block 10 and the face plate 11 are fixed to the extension 9 to form a coin chute open at its lower end and having the side opening 12 to receive the coin.

The transparent pane 13 is fixed to the base 7 at 14—14 and spaced therefrom to permit the passage of coins therebetween. The guides 15 and 16 are fixed to the base 7 between the base and the pane 13 to form the passage 17 forming a continuation of the coin chute. The weighted dog 18 is pivoted at 19 between the coin chute and the guide 15 and has its curved lower portion extending into the path of the coins descending from the chute. The rounded off deflecting lug 20 at the upper end of the dog is normally inoperatively retracted under the side of the chute, until the third coin enters.

The plate 21 is fixed to the base 7 at 14—14 and has the inclined edge 22. The top of the guide 16 is angularly cut away at 23 parallel with the inclined edge of the plate 21. The spacing block 10 of the coin chute is also cut away at 24 adjacent the plate 21, thus forming the angularly disposed coin passage 25.

The lever 26 is pivoted at 27 in front of the pane 13 and is normally urged into the inoperative position shown in Fig. 1 by the spring 28 expanding between the lever and the casing 1. The lever has the upwardly extending arm 29 which is adapted to impinge on the weighted stop 30 pivoted at 31 on the coin chute. When the lever 26 is in the inoperative position, the arm 29 forces the end of the stop 30 into the coin chute, preventing the descent of coins placed therein.

indicating an open circuit on incoming service line, which would render the coins ineffective.

The lever 26 also has the arm 32 extending downwardly therefrom. The detent 32 is fixed 5 in the end of this lever arm and is adapted to be advanced into position at the bottom of the passage 17 as shown in Fig. 2, to retain the initial coins.

The arm 33 extends laterally from the lever 10 26 and has the lug 34 depending therefrom. The contracting spring 35 connects the lug 34 to the soft iron armature 36 pivoted to the bracket 37 by the bolt 38. The electromagnet 39 is fixed to the casing 1 and coacts with the armature 36. 15 The armature is normally urged into inoperative position by the spring 40 expanding between the armature and bracket 37. The stop 41 limits the outward movement of the armature under the tension of the spring 32 by contacting the lug 20 42 depending from the bracket 37.

The disc 43 is fixed on the end of the shaft 44 and has the cam 45 adapted to cooperate with the stud 46 mounted on the lever 26. The cam shaft 44 is driven by the squirrel cage type induction 25 motor 47 which is energized by the inductive coil 48 wound on the usual laminated field magnet 49. The conventional electric clock reduction gearing 50 is interposed between the motor 47 and the camshaft 44 to time the rotation of the cam 30 45. This will vary for different uses of the apparatus. In the present instance, the motor and gearing is arranged to rotate the shaft 44 and cam 45 once every twelve hours and functions 35 as a horometric mechanism started by the dropping of the final coin.

The lever 51 is pivoted at 52 between the base 1 and the pane 13 and has the curved shoulder 51' adapted to be impinged upon by the coin in the angularly disposed passage 25, see Fig. 2. The 40 lever 51 is also provided with the lug 53 at its lower end extending into juxtaposition with the end of the set screw 54 in the bent over end of the lever arm 33.

The dielectric roller 55 is mounted at the upper end of the lever 51 and is adapted to impinge 45 on the spring contactor 56 having the non-burning contact point 57 in juxtaposition to the similar point 58 on the spring contactor 59. These contactors are mounted on the blocks 60—61, respectively, which are set in the dielectric base 62.

The wires 63, 64 are connected to the terminals 65, 66 and lead from the service line having the usual switch 67 interposed therein (see Fig. 4). The wires 68, 69 leading to the electromagnet 55 are connected to the service wires 63, 64, 55 at 65, 66, to energize the electromagnet whenever the switch 67 is closed.

The contactor 59 is connected to the terminal 66 by the wire 70. The opposed contactor 56 is 60 connected through the wire 72 to the terminal 73 having the consuming line wire 74 leading therefrom. The opposite wire 75 of the consuming line is permanently connected to the service line 63 through the terminal 76 and the conductor 77.

The terminals 73, 76 are connected through the wires 78—79 to the field coil 48 of the induction motor 47. Thus the induction motor is driven whenever current is supplied to the consuming line.

The apparatus operates substantially as follows: The switch 67 is first closed, permitting current to flow from the service line 63, 64, through the wires 68, 69 to energize the electromagnet 39. This attracts the armature 36, causing 75 it to assume the position shown in Fig. 2.

The spring 35 swings the lever 26 into the operative position (see dotted lines Fig. 2) upon the movement of the armature. This removes the set screw 54 from engagement with the lever 51, permitting the resilient contactors 56, 59 to straighten out and separate.

The movement of the lever 26 into operative position removes the arm 29 from beneath the stop 30 permitting it to retract of its own weight, thus opening the coin chute. The detent 32 is 10 also advanced into position, obstructing the bottom of the coin passage 17.

Three coins x of the proper denomination are then deposited in the coin chute one after the other. These coins fall into the passage 17 until 15 their movement is checked by the bottom coin coming to rest on the detent 32. The dog 18 is displaced by the uppermost coin, thus advancing the lug 20 into operative position beneath the coin chute.

The fourth coin x' subsequently placed in the coin chute is deflected laterally by the lug 20 and the top coin x . The coin x' comes to rest in a position between the guide 16 and the shoulder 51' of the lever 51, pressing the contactors 56, 25 59 together.

When the contactors are thus closed, current flows from the service line 64 through the wire 70, the contactors 56, 59, and the wire 72 to the consuming line 74. The current returns from the 30 point of consumption through the wires 75, 77 to the service wire 63.

Supplying the consuming line 74, 75 also energizes the field of the induction motor 47. The motor then slowly drives the cam 43 at the pre-determined speed through the reduction gearing 50. When the cam 45 approaches the end of its revolution, it impinges on the stud 46 and progressively tilts the lever 26 against the tension of the spring 35. This removes the detent 32 from 40 beneath the passage 17 permitting the three coins x to drop to the bottom of the casing 1.

Further movement of the lever 26 presses the setscrew 54 against the end of the lever 51, tilting the lever on its pivot 52; this increases the 45 distance between the guide 16 and the shoulder 51' permitting the coin x' to also drop to the bottom of the casing.

The setscrew 54 continues to engage the lower end of the lever 51, holding the contactors 56, 59 together after the coin x' has been dropped. The motor 47 is thus supplied with current until the projection 45 on the cam passes the stud 46. The stud 46 may be filed away as at 80 to insure accuracy in the operation of the cam.

When the projection 45 releases the stud 46, the spring 35 draws the lever 26 again into the position shown in dotted lines in Fig. 2. This withdraws the setscrew 54 from engagement with the lever 51, thus releasing the contactors 56, 59, 60 permitting them to straighten out and separate the contact points, see dotted lines Fig. 2. This shuts off the current from the consuming line and stops the operation of the motor 47. To restore the supply of current to the consuming line, it is 65 now necessary to deposit an additional four coins in the apparatus.

Opening the service switch 67 discontinues the operation of the electromagnet 39, permitting the armature 36 to be restored to the position shown 70 in Fig. 1 by the expansion of the spring 40. This also permits the lever 26 to assume the inoperative position shown in Fig. 1 by the expansion of the spring 28. This raises the arm 29 into engagement with the stop 30, forcing the stop into the 75

position illustrated in Fig. 3, and closing the coin chute. Advertant depositing of coins in the chute when the apparatus is in the inoperative position with the service switch open is thus prevented.

Should the service switch be prematurely opened during the course of the rotation of the cam 43 with a view to conserving the operation of the time switch, the lever 26 is immediately restored to the inoperative position, thus dumping the actuating coins in the apparatus. Deposit of additional coins then becomes necessary to complete the cycle of movement of the time switch.

Having thus described this invention, what is claimed and desired to be secured by Letters Patent is:

1. A time switch including switch contacts; a coin chute adapted to receive a plurality of coins and having a lateral passage; means for retaining the coins in said chute; coin controlled means in said passage for operating said switch contacts; a dog mounted in said chute at the entrance of said passage and adapted to be displaced, after a predetermined number of coins are deposited in said chute, to deflect a succeeding coin into said passage into engagement with said coin controlled means; and horometrical means adapted to move said retaining means and said coin controlled means to dump said coins after a predetermined interval.

2. A time switch including switch contacts; coin controlled means for operating said switch contacts; a coin chute adapted to receive a plurality of coins and having a lateral passage, means for deflecting one of said coins into said passage into engagement with said coin controlled operating means; a lever arranged to retain said coins in place in said coin chute and adapted to displace said operating means; an electromagnet connected to the main circuit of said switch and having an armature; a spring connecting said lever and armature and urging said lever into the operative position when said electromagnet is energized; a cam adapted to move said lever into the inoperative position, dumping the coins in said coin chute and displacing said operating means and dumping the coin in engagement therewith; a projection on said lever adapted to operatively engage said coin controlled means when said lever is moved into the inoperative position; and timed means for rotating said cam when said switch contacts are closed.

3. A time switch having contacts adapted to be connected to a service line; coin controlled means for operating said contacts; a coin chute adapted to deliver a coin into engagement with said coin controlled operating means; a lever having electromagnetic means connected to the service line and urging the lever into operative position; a cam adapted to move said lever into the inoperative position; a projection on said lever adapted to operatively engage said coin controlled means, dumping said coin and holding said contacts closed when said lever is moved into the inoperative position; a consuming line leading from said contacts; and timed means for rotating said cam motivated from said consuming line.

4. A time switch having a coin control comprising a coin chute adapted to receive a plurality of coins; a passage intersecting said chute; means for deflecting into said passage the last of a series of coins deposited in said chute; an operating lever in said passage adapted to be impinged upon by said coin to close the switch; a control lever

adapted to retain said coins in position in said chute; means for moving said control lever into the inoperative position and dumping the coins in said chute; and a projection on said control lever adapted to engage said operating lever when said control lever is in the inoperative position to dump the coins impinging there against and to maintain said switch closed after the coins have been dumped.

5. A coin controlled time switch comprising switch contacts; a coin chute adapted to receive a predetermined number of coins; a passage intersecting said chute, means for deflecting the last of said coins into said passage; an operating lever in said passage adapted to be impinged upon by said coin to close said switch contacts; a control lever adapted to retain said coins in position in said chute; a cam adapted to move said control lever into the inoperative position, dumping the coins in said chute; a motor adapted to drive said cam at a predetermined speed and forming part of a circuit controlled by said switch contacts; and a projection on said control lever adapted to engage said operating lever when the control lever is in the inoperative position to dump the coin impinging thereagainst and to maintain said switch contacts closed after the coins have been dumped to continue the operation of said motor until the cycle of movement of said cam is completed.

6. A time switch including switch contacts; coin controlled means for operating said contacts; horometrical means controlled by said contacts; a chute adapted to receive a predetermined number of coins and having a lateral passage; means for retaining the coins in position in said chute; means for deflecting a subsequent coin into said passage into engagement with said coin controlled means; and means actuated by said horometrical means for moving said retaining means and said coin controlled means to dump all of said coins at a predetermined interval after the operation of said contacts.

7. A time switch including switch contacts; coin controlled means for operating said contacts; horometrical means controlled by said contacts; a coin chute adapted to hold a predetermined number of coins and having a lateral passage; means for retaining the coins in said chute; means for deflecting a subsequent coin into said passage into engagement with said coin controlled operating means; and a cam actuated by said horometrical means adapted to move said retaining means and coin controlled means to release said coins at a predetermined interval after the operation of said contacts.

8. A time switch including switch contacts in an electric circuit; coin controlled means for operating said contacts; means for retaining a coin in engagement with said coin controlled means; horometrical means controlled by said contacts; coin releasing means actuated by said horometrical means for dumping said coin after a predetermined period of time; and means in said circuit for operating said coin releasing means if said circuit is opened intermediate said period of time.

9. A time switch interposed between a supply circuit, coin controlled means for closing said supply and consuming circuits; means for retaining a coin in engagement with said coin controlled means; horometrical means controlled by said coin controlled means; coin releasing means actuated by said horometrical means for dumping

said coins after a predetermined interval; and electro-magnetic means in said supply circuit and adapted to operate said coin releasing means when de-energized.

5 10. A time switch interposed in an electric circuit; coin controlled circuit closing means; means for retaining a coin in engagement with said coin controlled means; means for releasing said coin after a predetermined period of time; and

10 means for operating said coin releasing means if said circuit is opened before expiration of said period of time.

11. A time limit device of the character described, for permitting or preventing use of a device or mechanism, including: a control element adapted to be placed in active and inactive condition and to be associated with said device or mechanism in a manner to respectively permit or prevent the use thereof; actuating means for placing said control element in active condition; a time limit means for returning said control element to inactive condition at the end of a prescribed period, said time limit means comprising an electric motor as the motivating element thereof; circuit means for supplying electric energy to said motor; and means for returning said control element to inactive condition, such returning means being connected to said circuit means and having a part which moves in consequence of the reduction of the flow of electric energy in said circuit means to cause the return of said control element to inactive condition.

12. A time limit device of the character described, for permitting or preventing use of a device or mechanism, including: a control element adapted to be placed in active and inactive condition and to be associated with said device or mechanism in a manner to respectively permit or prevent the use thereof; coin controlled means operative to place said control element in active condition; a time limit means for returning said control element to inactive condition at the end of a prescribed period; and means operating in consequence of the stopping of said time limit means during said period to return said control element to inactive condition.

13. A time limit device of the character described for permitting or preventing use of a device or mechanism, including: a control element adapted to be placed in active and inactive condition and to be associated with said device or mechanism in a manner to respectively permit or prevent the use thereof; coin controlled means operative to place said control element in active condition; a time limit means for returning said

control element to inactive condition at the end of a prescribed period, said time limit means comprising an electric motor as the motivating element thereof; circuit means for supplying electric energy to said motor; and means operating in consequence of the stopping of the flow of current through said circuit means during said period to return said control element to inactive condition.

14. A time limit device of the character described, for permitting or preventing use of a device or mechanism, including: a control element adapted to be placed in active and inactive condition and to be associated with said device or mechanism in a manner to respectively permit or prevent the use thereof; coin controlled means operative to place said control element in active condition; a time limit means for returning said control element to inactive condition at the end of a prescribed period, said time limit means having an electric motor for operating the same; conductors forming an electric circuit for energizing said motor, and an electro-magnetic device connected to said circuit, having an armature which moves in consequence of a reduction of flow of electric energy in said circuit and causes movement of said control element to inactive condition.

15. An apparatus of the class described including a control element; actuating means adapted to render said control element operative; horological means adapted to be placed into operation by rendering said control element operative and adapted to restore said control element to inoperative condition after a prescribed period; means for stopping said horological means at any time and means operating simultaneously with said stopping of said horological means adapted to restore said control element to inoperative condition.

16. An apparatus of the class described including a control element; actuating means adapted to render said control element operative; electrically motivated horological means adapted to be placed into operation by said actuating means and adapted to restore said control element to inoperative condition after a prescribed period; an electrical circuit adapted to supply current to said electrically motivated horological means; a switch in said circuit and means operating in consequence of the opening of said switch intermediate said period adapted to restore said control element to inoperative condition.
